UNITED STATES PATENT OFFICE.

CHARLES HOLLAND, OF NEW YORK, N. Y.

PROCESS OF AND FURNACE FOR BURNING HYDROCARBON FLUIDS.

SPECIFICATION forming part of Letters Patent No. 275,490, dated April 10, 1883.

Application filed June 1, 1881. (No model.)

To all whom it may concern :

Be it known that I, CHARLES HOLLAND, of the city, county, and State of New York, have invented certain new and useful Improvements 5 in the Process of and Furnaces for Burning Hydrocarbon Fluids; and I do hereby declare the following to be a sufficiently full, clear, and exact description thereof to enable others skilled in the art to make and use the said in- 10 vention.

My invention relates to that class of furnaces in which water or steam and fluid hydrocarbons are introduced, volatilized, and burned with air, and has for its objects a 15 greater durability of apparatus, greater cleanliness, ready adaptability to different forms and qualities of hydrocarbon fluids, and greater facility of control and regulation.

The invention consists in a wrought-metal 20 retort containing a horizontal partition or shelf separating the hydrocarbon fluids from the steam or water, a superior form of such retort, an improved air-inlet tube or pipe, and an im- 25 proved method of regulating the supply of combustible matter to the different parts of the furnace.

I will now proceed to particularly describe the manner in which the said invention is made and operated, referring in so doing to the draw- 30 ings annexed and the letters of reference marked thereon.

Figure 1 represents a plan of my invention; Fig. 2, a vertical longitudinal section in the plane indicated by the dotted line xx in Fig. 1; 35 Fig. 3, a transverse section in the plane indicated by the dotted line yy in Figs. 1 and 2; and Fig. 4 shows an enlarged view of the jet-pipes or burners and air-tubes.

The same letters of reference apply to the 40 same parts in the several figures.

A represents a retort, made of wrought-iron or steel, securely welded at all of the joints or seams, and having a horizontal partition or shelf, A', extending from the perpendicular 45 end A² of the retort toward, but not reaching, the upwardly-inclined or curved end A³. In the end A² of the retort, above the partition A', is the oil induct or supply pipe B, and below the partition A' in the end A² is a water 50 or steam induct or supply pipe, C, and at the top of the upwardly-curved end A³ of the re-

tort is inserted a discharge or outlet pipe, D, through which the products of distillation are conveyed to be burned by a series of pipes, E, having branches E', provided with burners E². 55 The pipes E are arranged in sections, with intervening valves or gates, E³, by means of which the products of distillation from the retort may be admitted to or excluded from any one or more sections of the pipes E and their con- 60 nected branches and burners. These several burners are surrounded by conical tubes F, through which air is admitted and directed upon the current of gaseous or vaporous fuel discharged from the burners E². These tubes F are made 65 of chilled cast-iron, this material being found to be of more satisfactory durability than other metal, or than iron cast without chilling.

The several sections of pipes E and retorts A are arranged in the furnace in a manner 70 somewhat similar to that set forth in my Letters Patent numbered 239,785 and 239,786, and dated April 5, 1881, so that the retorts may be heated by jets of gaseous fuel burning under them before the supply of gaseous fuel is ad- 75 mitted to the entire furnace, and by opening the valves or gates E³ it may be afterward ad- mitted to the other burners in other parts of the furnace.

The operation of the invention is as follows: 80 Hydrocarbon fluid is admitted in a regulated supply at the pipe B to the chamber on the upper side of the partition A' in the retort A, and water or steam also admitted in regulated flow by the pipe C to the space in the retort A 85 below the partition A'. The retort is heated primarily by a small quantity of oil burned in a priming-pan, as in the case of the furnaces described in my patents already referred to. Hydrocarbon vapors and gases and steam in 90 superheated condition are delivered by the pipe D from the upper end of the retort A to the pipes E, and, escaping through burners E² under the retort A, mingled with the air entering the tubes F, burn and produce a high tempera- 95 ture in the retort. The more volatile part of the hydrocarbon fluid is vaporized before reaching the end of the partition A', and the less volatile portions, passing beyond the end of the partition A' and descending into the 100 lower chamber of the retort A are then com- mingled or combined with the steam and ef-

fectually distilled therewith and converted into gaseous fuel, thus avoiding deposits of carbon or other solid or tarry residuum in the retort and completely utilizing the hydrocarbon.

5 Having described my invention, what I claim therein as new and as originally of my invention is—

1. The method of burning hydrocarbon fluids with steam and air, consisting in introducing such fluid into a heated chamber, from which any imperfectly-volatilized portions descend to a more highly-heated compartment, and after mingling or combining with steam therein are discharged to the burners in gaseous or vapor- 15 ous form and burned with air, substantially as and with the effect set forth and described.

2. In an apparatus for burning hydrocarbons with steam and air, a retort of wrought-iron or steel, having compartments partitioned from each other by a horizontal shelf, and intercom- 20 municating, substantially as and for the purpose set forth.

3. In an apparatus for burning hydrocarbons with steam and air, a system of distributing- 25 pipes provided with burners and arranged in

sections intercommunicating by means of valves or gates, in combination with a retort or retorts so arranged and connected as to distill the liquid hydrocarbon, and heated by flame supplied from one or more of said sections, 30 substantially as and for the purpose set forth.

4. In an apparatus for burning hydrocarbons with steam and air, the combination of the horizontally-partitioned retort A, supplied with steam or water and hydrocarbon fluid, 35 the outlet-pipe D, sectional pipes E, gates or valves E³, branches E', and burners E², substantially as and for the purpose set forth.

5. In an apparatus for burning hydrocarbons with steam and air, the combination of the 40 partitioned retort A, supplied with steam or water and hydrocarbon fluid, the pipe D, and series of pipes E, provided with valves E³, and burners E², with the air-tubes F, substantially as and for the purpose set forth.

CHARLES HOLLAND.
